UNITED STATES PATENT OFFICE.

CHARLES F. WHORF, OF ST. LOUIS, MISSOURI, ASSIGNOR OF TWO-THIRDS
TO CHARLES A. WHORF AND FRED E. WHORF, BOTH OF SAME PLACE.

STOVE.

SPECIFICATION forming part of Letters Patent No. 351,892, dated November 2, 1886.

Application filed March 7, 1884. Serial No. 123,426. (No model.)

To all whom it may concern:

Be it known that I, CHARLES F. WHORF, of St. Louis, Missouri, have made a new and useful Improvement in Stoves, of which the following is a full, clear, and exact description, reference being had to the annexed drawings, making a part of this specification, in which—

Figure 1 is a front elevation, half in vertical section, of the improved stove; Fig. 2, a plan, a portion of the top plate being broken away to exhibit the interior; and Fig. 3, a vertical section on the line 3 3 of Fig. 1.

The same letters of reference denote the same parts.

The present invention is an improvement more especially in what are termed "gas" or "gasoline" stoves. The improvement relates to the construction of the oven, to the heating arrangement at each side of the oven, and to the combination of the various parts, all substantially as hereinafter described, and designated in the claims.

A, Fig. 1, represents the stove in question. Considered generally, the stove consists of an oven and heating arrangement at each side of the oven, the top of the oven being flush, or thereabout, with the tops of the heating arrangements at the sides of the oven, the oven being heated by its own burner, and being mounted upon a base which serves to support the entire superstructure, and also is preferably made to contain a hot-closet.

B represents the oven. C represents the burner for heating the oven. The heat-currents from the burner enter the flue-space D beneath the oven. They pass thence into the flue E at the rear end of the oven. They flow upward through the last-named flue into the space F above the oven. The currents thence pass downward into the oven to the lower part thereof, and from the oven the heat-currents pass outward, partly through the openings b b at each side of the oven, and partly into a flue, g, formed in the oven-door G. The heat which escapes through the openings b b passes directly into the open air, and that portion which passes into the flue g escapes therefrom through the outlets g', all as indicated by the various arrows in the upper portion of Figs. 1, 3. Access is

had to the interior of the oven by opening the door G. In this manner the heat is applied to the bottom, to the rear end, to the top and interior of the oven, and to the front of the oven, and the sides of the oven are somewhat heated by reason of the presence of the burners H H at each side of the oven. The stove-top I is extended laterally at I' I', which extensions, in connection with the burners H H, form the heating arrangements above alluded to as being at each side of the oven. The central portion, I, of the stove-top is heated by means of the heat passing into the space F at the top of the oven. In this manner the capacity of a gas-stove is considerably increased, and at the same time ample table-room is provided at the top of the stove. The burners C H H are of the ordinary character, and are supplied by means of the tubes e h h in the ordinary manner. The burner C, for heating the oven, may be left open to the surrounding air; but I prefer to utilize the heat, which otherwise might be wasted therefrom, for heating a hot-closet, J, which is made to occupy the principal portion of the space beneath the oven and above the base K. The air for supplying the burner Centers in such case through any suitable apertures, c' c', in the bottom of the hot-closet, or it may be supplied thereto in any other suitable manner.

The top b' of the oven in the drawings has but a single perforation, b'; but, if desired, the top of the oven may have several perforations, or be constructed in any other manner so as to enable the heat from the rear flue, E, to enter and pass downward uniformly into the oven.

In presenting this application I wish to disclaim the construction patented to me February 6, 1883, and numbered 271,670. In that oven the heat-currents pass from beneath the oven, upward at the sides of the oven, thence downward through the interior of the oven to the bottom of the oven, and finally upward at the back of the oven. In the present oven the heat-currents pass from beneath the oven upward at the back of the oven, thence downward through the interior of the oven, and thence outward from the interior of the oven at or near the bottom of the oven.

I am also aware that a steam cooking appli-

ance has been used in which steam-jacketed utensils have been supported at the sides of a central oven; but the supports for such utensils are in no sense extensions of the oven-top, 5 nor is the oven-top adapted for a table-top, nor can it be used in conjunction with the utensil-supports for heating or for upholding a cooking utensil.

I claim—

10 1. The oven B, having the flues D E F g and the outlets b b, as and for the purposes described.

15 2. A gasoline or gas stove having the central oven, B, and the side extensions, I' I', and the burners C H H, said side extensions being

in the plane of and extensions of the oven-top, and said oven having a flue leading from the burner C upward to beneath the oven-top, substantially as described.

3. An oven having a flue at its rear communicating with the interior of the same at its top, and provided with a hollow door having apertures near its bottom upon the inside and apertures near the top on the outside, substantially as described. 20

CHARLES F. WHORF.
